UNITED STATES PATENT OFFICE.

RICHARD HENRY CRONINGER, OF OAKWOOD, OHIO, ASSIGNEE, BY MESNE ASSIGNMENTS,
TO THE DAYTON ADDING MACHINE & TIME LOCK COMPANY, OF DAYTON, OHIO, A
CORPORATION OF OHIO.

RECORDING DEVICE.

1,263,530.

Specification of Letters Patent. Patented Apr. 23, 1918.

Application filed April 30, 1917. Serial No. 165,306.

To all whom it may concern:

Be it known that I, RICHARD HENRY CRONINGER, a citizen of the United States, residing at Oakwood, in the county of 5 Montgomery and State of Ohio, have invented certain new and useful Improvements in Recording Devices, of which the following is a specification, reference being had therein to the accompanying drawing.

10 This invention relates to recording devices and more particularly to a device for placing upon a time record a mark to indicate whether the hour recorded was "A. M." or "P. M."

15 Time recording devices heretofore used have employed A. M. and P. M. indicating mechanisms which were automatically controlled by the clock mechanism, but these mechanisms, for the most part at least, were 20 of a complicated construction, comprising a large number of parts, which not only rendered the device expensive in production and difficult in maintenance, but also resulted in imposing so much of a load on 25 the clock mechanism as to cause a serious drag thereon which interfered with the accuracy of both the clock and the A. M. and P. M. mechanism.

The object of the present invention is to 30 provide a device of this kind which will be very simple in construction and operation, comprising but a few parts and having these parts of such a character that they can be easily produced, and will require no 35 fine adjustments to maintain the mechanism in an operative condition. It is also an object of the invention to so construct and arrange the parts thereof that the operation of the same will add but little to the load 40 on the clock mechanism, and will not interfere with its accuracy.

In the accompanying drawings Figure 1 is a bottom plan view of a time recorder showing the form and the supporting device therefor; Fig. 2 is a side elevation of the same showing the form, the A. M. and P. M. mechanism, and that part of the clock mechanism which actuates the form and the A. M. and P. M. mechanism; Fig. 3 is a sectional view taken on the line $x-x$ of Fig. 2 looking in the direction of the arrows; and Figs. 4 and 5 are detailed views show-

ing modified arrangements of the A. M. and P. M. mechanism.

In carrying out my invention I employ 55 a time recorder from which a record may be taken and I arrange adjacent to this time recorder a marking device which is movable into and out of position to make a mark upon the record when the impression is taken. There may be either one or two of these marking devices. If two are employed, one carries the letter "A" to indicate A. M., and the other carries "P" to indicate P. M., and they are so arranged 60 that only one of them will be in printing position at one time, and means are provided for reversing their positions at noon and at midnight. If one marking device only is employed the mark may be either 65 "A" or "P," and if the mark is "A," for example, the absence of any mark at all on the record will indicate that the hour recorded is P. M. The marking device, or devices, may be moved into and out of 70 operative position in any suitable manner, but I preferably employ an actuating bar or rod, which is engaged by a cam connected with the clock mechanism and so controlled that the bar will be moved in one direction 75 at noon and in the other direction at midnight, and that this movement will be imparted to the marking device. The mechanism may be employed with recording 80 mechanism of various kinds and the marking devices and the means for actuating the same may take various forms, that here shown being used for the purpose of illustration.

In the particular embodiment of the invention here illustrated I have shown the same as applied to a time recorder comprising a flat form which consists of a clock-like dial, 1, and movable indicating devices 2 and 3 corresponding to the hands of a 95 clock and adapted to print on the record a mark indicating the hour and minute at which the record is taken. This form is carried by a frame or casing 4, which is arranged adjacent to, and preferably rigidly 100 connected with, a frame 5 of a clock mechanism, a portion only of which is here shown. The indicating devices 2 and 3 are carried by telescoping shafts 6 and 7 which extend

through the frame 4 and are connected with the clock mechanism in a well known manner. Coöperating with the form is a suitable device, such as a platen 8, by means of 5 which a record may be taken from the form. The mechanism so far described is of a well known character and as it forms no part of the present invention, aside from its combination with the A. M. and P. M. mechanism, it need not be illustrated, or described, 10 in detail. As has been explained the A. M. and P. M. mechanisms may comprise either one or two marking devices which are mounted for movement into and out of an operative position with relation to the form so that when a marking device is in printing position it will make its mark upon the record when the impression is taken. In that form of the device shown in Figs. 1 to 15 20 3 I have employed two marking devices, 9 and 10, which are alternately movable into operative relation to the form. In the present arrangement of the device these marking devices have movement transversely to the plane of the form and comprise printing type connected with, and preferably carried by, actuating bars 11 and 12, which are slidably mounted in the frame or casing 4. Acting upon each of these bars 25 is a spring 13 which tends to move the same in a direction which will carry the marking device into its inoperative position, that is, will retract the same beyond the plane of the printing surface of the form so that it 30 35 will not be engaged by the platen when an impression is taken from the form. Suitable means are employed for imparting longitudinal movement to the actuating bars 11 and 12, which, in the present construction, 40 have the marking devices rigidly secured to the ends thereof and constitute type carriers, and this means as here illustrated comprises a pair of cams, one for each bar, which are 45 operatively connected with the clock mechanism and are so arranged that one cam will engage its bar, move the same against the tension of the spring and hold the same in that position for a period of twelve hours, and at the end of that period will release 50 the bar to permit it to be retracted by its spring. Simultaneously with the retraction of the one bar the other bar will be engaged by its cam and move against the tension of its spring to carry its marking device into 55 operative position, and will retain its marking device in such position for a period of twelve hours, at the end of which the positions of the marking devices will be again reversed, thus maintaining one or the other 60 of the marking devices always in operative position. The cams for actuating the marking devices may be of any suitable character and arrangement. As here illustrated they are substantially semicircular in form, as 65 shown at 14 and 15 in Fig. 3, and are se-

cured to the face of a gear 16 which meshes with one of the gears of the clock mechanism. In the present instance the gear 16 meshes with the hour pinion 17, but it is immaterial with what part of the mechanism 70 the gear 16 is connected so long as it is caused to make one complete revolution in twenty-four hours. The gear 16 may be mounted in any suitable manner and located in any position which will properly accommodate it to the desired location of the marking devices. In the present construction it is carried by shaft 18 having bearing at its lower end in frame 4 and having bearing at its upper end in a bearing socket 19, 80 which is screw-threaded into the frame member 5 of the bar.

A single cam may also be utilized for actuating the two bars and, as illustrated in Fig. 4, this may be accomplished by arranging the two bars, there shown at 20 and 21, on diametrically opposite sides of the cam carrying device, or gear, 22, and forming the cam 23 of such length that as one end thereof releases the one bar the other end thereof will engage and actuate the other bar, the ends of the cam being, in this form as well as in the other forms illustrated, beveled to facilitate the engagement and retraction of the bars.

As has been explained the device may, if desired, be utilized with a single marking device. In fact in many uses of the device the single marking device is preferable as it reduces the number of parts, the cost of 100 production and the load imposed upon the clock mechanism, and the record produced thereby is equally definite and satisfactory. In Fig. 5 I have illustrated a form of the device employing a single marking device 105 and have shown the actuating bar therefor at 24. The cam 25, which is carried by the gear 26 is semicircular in shape so that the actuating bar will be moved in one direction at noon and in the other direction 110 at midnight, thus causing it to make a mark upon the record during one half of the day and retaining the same in an inoperative position during the other half of the day.

The operation of the device will be readily understood from the foregoing description and it will be apparent that I have produced a device which is exceedingly simple both in construction and operation; which is 120 positive and accurate in its operation; and which will require very little power to operate it and hence will add but little to the load on the clock. Further, it will be apparent that the device requires no fine adjustments, but that the length of movement of the actuating bars 11 and 12 may be regulated to bring the marking devices into proper relation to the form by adjusting the cam carrying device by means of the screw- 125 130

threaded bearing 19. Further it will be apparent that the construction and arrangement of the device is such that it will operate with equal reliability and accuracy 5 in any position in which it may be placed. The position illustrated in the drawings, in which the mechanism is placed in a vertical position with the form facing downward, being chosen for the purpose of illustration 10 only.

While I have shown and described one embodiment of my invention I wish it to be understood that I do not desire to be limited to the details of construction as various 15 modifications will occur to a person skilled in the art.

Having now fully described my invention, what I claim as new and desire to secure by Letters Patent, is:—

20 1. The combination with a recording device, comprising an adjustable form and clock mechanism to operate the same, of a marking device movable into and out of an operative position adjacent to said form, 25 an actuating device connected with said marking device, and a cam operatively connected with said clock mechanism and arranged to engage said actuating device and cause said marking device to be actuated in 30 timed relation to the movement of said form.

2. The combination with a recording device, comprising an adjustable form and clock mechanism to operate the same, of a 35 marking device movable into and out of operative position adjacent to said form, a reciprocatory bar connected with said marking device to actuate the same, and a cam operatively connected with said clock mechanism and arranged to engage said bar and cause said marking device to be actuated in 40 timed relation to the movement of said form.

3. The combination with a recording device, comprising an adjustable form and clock mechanism to operate the same, of a marking device movable into and out of operative position adjacent to said form, a reciprocatory bar connected with said marking device to actuate the same, and an elongated cam operatively connected with said clock mechanism and arranged to engage said bar and cause said marking device to be actuated in timed relation to the movement of said form, the length of said cam being such that said marking device will be retained in its adjusted position for a predetermined period of time.

4. The combination with a recording device, comprising an adjustable form and clock mechanism to operate the same, of a marking device movable into and out of an operative position adjacent to said form, an actuating member connected with said marking device to actuate the same, a spring

tending to move said marking device into its inoperative position, and a cam operatively connected with said clock mechanism and arranged to engage said actuating member to move said marking device into its operative position and retain the same in said position for a predetermined period of time. 70

5. The combination with a recording device, comprising an adjustable form and clock mechanism to operate the same, of a marking device movable into and out of an operative position adjacent to said form, an actuating member connected with said marking device, and a rotary cam operatively connected with said clock mechanism 80 and arranged to act upon said actuating member to cause said marking device to be actuated in timed relation to the movement of said form.

6. The combination with a recording device, comprising an adjustable form and clock mechanism to operate the same, of a marking device movable into and out of an operative position adjacent to said form, an actuating member connected with said marking device, a gear operatively connected with said clock mechanism, and a semicircular cam carried by said gear and arranged to engage said actuating member to cause said marking device to be actuated. 90

7. The combination with a recording device, comprising an adjustable form and clock mechanism to operate the same, of a plurality of marking devices movable into and out of operative positions adjacent to 100 said form, a separate actuating device for each of said marking devices, and a device having cam surfaces arranged to act upon said actuating members to cause said marking devices to be alternately moved into and 105 out of their operative positions.

8. The combination with a recording device, comprising an adjustable form and clock mechanism to operate the same, of a plurality of marking devices movable into 110 and out of operative positions adjacent to said form, actuating members connected with the respective marking devices, a rotary device operatively connected with said clock mechanism, and two semicircular cams carried by said rotary device and arranged in opposed relation and adapted to engage the respective actuating members and cause said marking devices to be moved alternately into and out of their operative positions. 115

9. The combination with a recording device, comprising an adjustable form and clock mechanism to operate the same, of a reciprocatory bar mounted adjacent to said form for movement transversely thereof, a marking device carried by said bar and adapted to be moved into and out of operative position by the movement of said bar, and a cam operatively connected with said clock mechanism and arranged to engage 125 130

4
said bar to actuate the same and impart movement to said marking device.

10. The combination with a recording device, comprising an adjustable form and 5 clock mechanism to operate the same, of a reciprocatory bar mounted adjacent to said form for movement transversely thereof, a marking device carried by said bar and adapted to be moved into and out of operative 10 position by the movement of said bar, a spring acting on said bar to move said marking device into its inoperative position, and a cam operatively connected with said clock mechanism and arranged to engage 15 said bar and move the same against the tension of said spring to move said marking device into its operative position.

11. The combination with a recording device, comprising an adjustable form and 20 clock mechanism to operate the same, of a reciprocatory bar mounted adjacent to said form for movement transversely thereof, a marking device carried by said bar and adapted to be moved into and out of operative 25 position by the movement of said bar, a spring acting on said bar to move said marking device into its inoperative position, a gear rotatably mounted in a plane extending transversely to the line of movement 30 of said bar, and a cam carried by said gear and arranged to engage said bar and actuate the same to impart movement to said marking device.

12. The combination with a recording device, comprising a flat form adjustable to 35 make different records, a supporting frame for said form, and clock mechanism arranged adjacent to said frame and operatively connected with said adjustable form, 40 of a bar mounted in said frame for lengthwise movement transversely to the plane of said flat form, a gear rotatably mounted near the end of said bar and connected with said clock mechanism, a semicircular cam 45 carried by said gear and arranged to engage said bar and move the same in one direction,

and a spring connected with said bar and tending to move the same in the opposite direction.

13. A device of the character described, 50 comprising a reciprocatory bar, a marking device carried by said bar and movable into and out of operative position by the reciprocation of said bar, a spring tending to move said bar in one direction, a gear mounted for rotation in a plane extending transversely to said bar near the end thereof, and an elongated cam carried by said gear and arranged to act upon said bar to impart movement thereto and hold the same in its 55 adjusted position.

14. The combination with a recording device, comprising an adjustable form and clock mechanism to operate the same, of a marking device movable into and out of an 60 operative position adjacent to said form, an actuating bar connected with said marking device to move the same into and out of its operative position, and means operatively connected with said clock mechanism and 65 acting on said bar to impart movement thereto.

15. The combination with a recording device comprising an adjustable form and clock mechanism to operate the same, of a 70 reciprocatory bar, a marking device carried by said bar, operating means connected with said clock mechanism and engaging said bar to move the same in one direction, and a spring acting upon said bar to move the 75 same in the opposite direction.

16. The combination with a recording device, comprising an adjustable form and clock mechanism to operate the same, of a marking device movable into and out of an 80 operative position adjacent to said form, and a cam operatively connected with said clock mechanism and acting on said marking device to impart movement thereto.

In testimony whereof, I affix my signature 85 hereto.

RICHARD HENRY CRONINGER.
